UNITED STATES PATENT OFFICE.

LÉON DELPEUT, OF LISBON, PORTUGAL.

CAN-OPENING DEVICE.

1,108,719.

Specification of Letters Patent.

Patented Aug. 25, 1914.

Application filed September 26, 1910. Serial No. 583,838.

To all whom it may concern:

Be it known that I, LÉON DELPEUT, a citizen of the Republic of France, residing at 40 Rua do Corpo Santo, Lisbon, Portugal, 5 merchant, have invented certain new and useful Improvements in Can-Opening Devices, of which the following is a specification.

This invention relates to improvements in 10 cans, tins and the like and opening devices therefor.

In the improved tin, one wall of the box which is preferably bordered by a rib and weakened along a line to facilitate tearing 15 of the metal, can be torn by twisting it around an appropriate key operating on a tongue fixed to said wall or forming part of the same.

The present invention consists essentially 20 in the arrangement of the tongue and of a guide piece combined with the tongue and which insures the metal being torn along the proper line.

The annexed drawing illustrates various 25 examples of construction of the device.

Figure 1 is an elevation of the inner face of a wall of the box. Fig. 2 is a section taken on the line A A of Fig. 1. Figs. 3 and 4 are elevations showing other forms 30 of construction. Figs. 5 to 9 illustrate modified forms of the tongue and guide.

In the inside of the wall 1 for instance the top of the metal tin or box which is provided adjacent its edges with a weakened 35 line 2, and also possibly with a rib 3 formed along this line, is secured a small piece of metal 4 of a more or less malleable nature and which I term a guide. This guide, the shape of which can vary, for instance, it 40 can be straight or curved, is placed along a part 5, 5 of the weakened line, which has a small slit 6 just sufficient for the passage of a tongue 7.

The tongue 7 consists of a strip of sufficiently strong tin of narrow width. The 45 length of the tongue is such that being folded in the slit at about its middle, its inner end passes around the guide 4 and is soldered at 8 to the lid 1 of the box by 50 simple fusion of the tin of the tongue and of the cover. The projecting extremity is sufficiently long to be easily grasped by the fingers and rolled around the key.

When the tongue is introduced in the 55 slit, the edges of the same are flattened against the tongue and the tin melted to

close the joint, or a little solder can be put on the outside for this purpose as there is no fear of it passing through the slit.

The guide 4 is fixed to the lid 1 and the 60 tongue 7 when the slit is closed without the necessity of being especially soldered. The fusion of the tin of the cover, the guide and the tongue and the flow of a very small quantity of tin through the slit is sufficient 65 to maintain the guide in place. The guide prevents the tongue from tearing a narrow strip out of the tin lid and causes the tear in the lid to follow the weakened line. The malleability of the guide 4 has the effect of 70 the tearing of the cover to be gradual and consequently preventing the tongue from being torn off. An important feature of this arrangement is that as the guide is arranged between the tongue and the cover 75 greater resistance is secured and for insuring the tearing of the cover than if the guide were formed by a direct extension of the tongue. In the latter case when the tongue is wound around the key, the part 80 of the tongue adjacent the slit is drawn vertically and lifts the corresponding portion of the cover at the same time sharply curving it so that the solder fixing the tongue to the cover is immediately submitted to severe stresses of flexion and traction which often cause breakage to prevent 85 which, it has been the custom to use a great deal of solder to produce a stronger construction.

With the new device the resistance to the flexion of the guide superposed to the tongue has the effect of preventing the edge of the slit from curving easily and of consequently only submitting the inner portion of the tongue to an insignificant traction during tearing. The result is that the tongue does not require to be fixed exceedingly strongly and can be fixed by the simple fusion of the tin plate which forms the tongue and the 90 cover without the addition of solder proper. There is no need to use solder to fix the guide to the cover, nor even to block the small slit through which the tongue passes. This suppression of solder is of great 95 importance hygienically. From Figs. 1, 3 and 4 it can be seen that the form and position of the tongue and guide can vary. In these constructions the rib 3 is stopped at each side of the guide.

The present device has advantages over 100 those of a similar kind particularly by rea-

son of the distinct or separate making of the two pieces constituting the guide and the tongue.

The pieces can be easily made without waste, each element being cut from suitable plate in such a way that its length is parallel with the direction in which the plate has been rolled, in order to utilize the resistance of the metal to the best advantage; this would be impossible if the guide and the tongue were made in a single T-shaped piece.

Only a small slit need be made in the wall of the box which slit is easy to make without any special stock of tools.

With the present device the starting and guiding of the tear in the lid are so well assured that there is no need to take into account the rolled direction of the sheet metal when making the boxes which results in reducing waste and saving of cost of production. The opening device can be arranged in a corner of the lid or at the side thereof.

There is no danger of solder penetrating into the box.

Instead of placing the guide against the cover and then fixing the tongue above this guide it is advantageous in certain cases, particularly when the use of solder is not inconvenient, to solder the guide and the tongue together; as they are placed on the cover the guide thus provided with its tongue is heated so that the solder employed will also serve to fix the guide, tongue and cover together and also to block the slit of the latter.

Figs. 5 and 6 illustrate opening members thus made in advance, 4 represents the guide and 7 the tongue which are soldered together. A straight band 4 folded to a V-shape could be used, the arms of which follow the direction of the lines provided for tearing the cover. The tongue 7 then passes over the folded part. This arrangement has the advantage of considerably strengthening the opening member at the point where the resistance would be greatest; further if the band is cut in the direction of rolling the arms of the same when folded offer the greatest possible resistance to produce the tearing of the lid, further the manufacture of this guide does not necessitate any special tool and the bending can be made with the same facility, whatever the angle chosen. The reinforcement resulting from the superposition of the guide and the tongue can be obtained also without the guide and the tongue being absolutely distinct from one another; they can be made of a single piece of tin plate conveniently cut and bent as indicated for example in Fig. 8. The tongue 7 is then cut so that its base is widened out to

form a plate (shown in dotted lines) which when folded along the transverse line 9—9 forms the guide 4.

Fig. 9 shows another form of construction in which the tongue 7 has a long and narrow extension which is folded three times so as to form a V-shaped guide 4 as in the case of Fig. 7, and a transverse piece 10 connecting this guide to the tongue. The band of tin plate is straight before being folded.

Claims:

1. The combination with a tin can having a slit therein, of a device for opening said can comprising a guide secured to the inner face of the wall of the can to be broken through, one of the edges of said guide being placed close to the slit in said wall, and a tongue placed through said slit and under the guide and secured to said wall, to break through the wall through the medium of said guide.

2. The combination with a tin can having a slit in its wall to be broken through, of a device for opening said can comprising a tongue passed through said slit, the inner end of said tongue being secured to said wall at a distance from said slit, and a guide placed between the said wall and tongue, between said slit and the point at which the inner end of the said tongue is placed transversely to the tongue.

3. The combination with a tin can having a slit therein, of a device for opening said can comprising a tin laminated guide secured beneath the wall to be broken through, near the slit in said wall, and a tin tongue placed through the said slit and underneath the guide, the directions of the laminating of the guide and of the tongue crossing one another.

4. The combination with a tin can having a slit therein, of a device for opening said can comprising a guide secured beneath the wall to be broken through, a tongue passed through said slit and secured to said wall, the guide being bent in V-shape and the bend thereof placed adjacent said slit between the wall and the tongue.

5. The combination with a tin can having a slit therein, of a device for opening said can comprising a guide secured beneath the wall to be broken through and having one edge thereof placed adjacent said slit, and a tongue placed through said slit and underneath the guide, said guide and tongue being made of a single piece of bent tin.

In testimony, that I claim the foregoing as my invention, I have signed my name in presence of two subscribing witnesses.

LÉON DELPEUT.
